UNITED STATES PATENT OFFICE.

WILLIAM M. ERWIN AND WILLIAM F. STRETCH, OF HANFORD, CALIFORNIA.

AUTOMOBILE-RADIATOR CAP.

1,389,495.

Specification of Letters Patent. Patented Aug. 30, 1921.

Application filed December 30, 1920. Serial No. 434,016.

To all whom it may concern:

Be it known that we, WILLIAM M. ERWIN and WILLIAM F. STRETCH, citizens of the United States, residing at Hanford, in the 5 county of Kings and State of California, have invented certain new and useful Improvements in an Automobile-Radiator Cap, of which the following is a specification.

This invention relates to caps for automobile radiators and the like.

The primary object of the invention is to provide a hinged cap of this character which may be readily applied to the necks of various standard forms of radiators without necessitating any change being made in the neck, the cap ordinarily employed being unscrewed and the cap constituting this invention substituted.

Another object is to provide such a cap so 20 constructed as to eliminate the necessity of unscrewing and removing the cap for filling the radiator and the annoyance consequent to finding the thread when replacing the cap thereby greatly facilitating the operation 25 and avoiding burning of the fingers when the radiator is hot.

Another object is to provide a cap having a hinged closure equipped with a positive clamp to hold the closure tightly seated with- 30 out the use of springs and which closure cannot be jarred loose by vibration.

With these and other objects in view the invention consists in certain novel features of construction as hereinafter shown and described, and specifically pointed out in the 35 claim.

In the accompanying drawing:

Figure 1 represents a side elevation of the cap constituting this invention shown ap- 40 plied, the neck of the radiator filling opening being shown in section.

Fig. 2 is a central vertical section of a cap; and

Fig. 3 is a similar view with the two parts 45 constituting the cap shown arranged in juxtaposition ready for assembling.

The cap C constituting this invention com- 50 prises a sleeve or collar 1, a portion of which is externally threaded as shown at 2 and adapted to be screwed into the mouth M of the radiator neck N (see Fig. 1). This sleeve 1 carries a laterally extending flange 4 near its upper end provided on its perime- 55 ter with an upstanding lip 5 forming be- tween it and the top edge 3 of the sleeve an annular seat 6 to receive a gasket 7. The lip

5 extends in a plane beyond the sleeve edge 3 and is designed to fit in a groove 11 in the hinged lid or closure member 10 of the cap C. The inner wall of the groove 11 of lid 10 constitutes the outer face of a rib 12 which is designed to rest on the gasket 7 and effect a watertight joint between lid 10 and the sleeve.

The sleeve 1 has a pair of laterally spaced 65 apertured ears 8 at one side of the outer face of flange 4 and is designed to receive between them a similar ear or lug 13 connected therewith by a pintle to form the hinge for lid 10.

A nose 14 carried by lug 13 is designed to 70 engage sleeve 1 and form a stop to limit the opening movement of lid 10.

The lid 10 has a latch 15 pivoted thereto preferably at a point diametrically opposite the lug 13 and which is adapted to engage 75 a catch 9 carried by the sleeve flange 4 at a point diametrically opposite the hinge member 8 thereof, said latch 15 having a hook 16 which engages catch 9 and locks the lid closed until released. This catch 9 has an 80 enlargement 17 which operates when the latch is closed to throw said latch off center and prevent its release by jars or vibrations.

In the use of this cap the threaded sleeve 1 is inserted in the radiator neck end as shown 85 in Fig. 1 and when it is desired to fill the radiator all that is necessary is to release latch 15 and open the hinged closure member 10, the stop 14 operating to hold the lid raised ready for closing after the radiator 90 has been filled. The rib 12 bearing on the gasket 7 and the interlocking engagement of lip 5 with groove 11 operates to insure a wa- 95 tertight connection between the sleeve and its closure.

The preferred embodiment of the invention is disclosed in the drawings and set forth in the specification, but it will be understood that any modifications within the scope of the claimed invention may be made 100 in the construction without departing from the principle of the invention or sacrificing any of its advantages.

What we claim is:

An automobile radiator cap comprising a 105 threaded sleeve for engagement with the radiator neck, and having a flange L-shaped in cross section on its outer face below its upper edge, the long arm of said flange up- 110 standing and being concentric with said edge and extending in a plane above it, a gasket seat being formed between said edge and said

upstanding flange portion, a lid shaped to fit said flanged sleeve end and having an annular groove to receive the upstanding edge of said sleeve and a rib to fit in said gasket seat, said lid and sleeve being hingedly connected and the sleeve provided with a cam catch and the lid with a coöperating hook

shaped latch whereby the latch is thrown off center when engaged with said catch to prevent its accidental release.

10

In testimony whereof, we affix our signatures hereto.

WILLIAM M. ERWIN.

WILLIAM F. STRETCH.
